UNITED STATES PATENT OFFICE.

JOHN MAGEE AND FRANK A. MAGEE, OF CHELSEA, ASSIGNEES TO THE
MAGEE FURNACE COMPANY, OF BOSTON, MASSACHUSETTS.

MAGAZINE-STOVE.

SPECIFICATION forming part of Letters Patent No. 252,232, dated January 10, 1882.

Application filed July 25, 1881. (No model.)

To all whom it may concern:

Be it known that we, JOHN MAGEE and FRANK A. MAGEE, both of Chelsea, in the county of Suffolk and State of Massachusetts, citizens of the United States, have invented a certain new and useful Improvement in Magazine or Base-Burning Stoves, of which the following is a full, clear, and exact description, reference being had to the accompanying drawings, forming a part of this specification, in explaining its nature, in which—

Figure 1 is a vertical central section of our improved stove. Fig. 2 is a vertical cross-section at right angle to the section shown in Fig. 1. Fig. 3 is a detail view, enlarged, of the door to the magazine, and Figs. 4 and 5 relate to features hereinafter more fully described. Fig. 6 is a perspective of our stove; and Fig. 7 is a view, also in perspective, of a plate and removable door, which are adapted to be substituted for the doors and plate shown in Fig. 6 in converting a close stove into an open grate.

This invention embraces, first, means whereby a magazine or base-burning stove may be readily converted into an open-grate stove; second, improved mechanism for adjusting the size of the outlet of the magazine; third, means whereby the gas is prevented from escaping through the magazine into the room, and, fourth, the arrangement of side and front lights in relation to the grate.

In the drawings, A represents the ash-pit; a, the ash-pit door; B, the grate; C, the fire-pot; D, the combustion-chamber; d, the opening connecting the combustion-chamber with the diving-flue d' and with the direct flue d''. E is the magazine. F is a removable plate containing doors f. This plate is fastened to the frame of the stove by screws f', and when it is desired to change the stove from a close one to an open grate this plate F is removed and the plate or frame f'', adapted to be fastened to the frame of the stove by the screws f'', is substituted. This frame f'' has a large opening, f'', a removable blower, f'', and a hood, f'', (represented in Fig. 7,) and when used it gives the stove all the features of an open-grate stove.

The size of the outlet e of the magazine is varied by means of the front plate, e', which is hinged at e', and is provided with wings e'',

extending beyond or overlapping the side plates, e', of the magazine, and by the latch e'', having the graduated notches e'', pivoted at e', and the catch e'' of the swinging plate e''. It will be observed that by lifting the latch the plate e'' may be moved out or in in relation to the sides e' of the magazine and then locked, and that by so doing the size of the outlet may be increased or diminished as desired. This adjustment permits of the use of coal of any size.

In order that gas may not escape through the opening e'', by which the coal is supplied to the magazine, we have provided, in substance, a double door for closing it, or a door consisting of two plates, the under of which is adapted to close the opening before the upper one is entirely shut, and any gas that may escape from the magazine past the lower plate is taken from the chamber or recess between them through the escape-holes e''' into the passage or flue e''', connecting with the direct escape and diving flue.

The door G, to more minutely describe it, consists in the upper plate, g, which is pivoted at g', and which, when closed, bears upon the shoulders g'', and the lower plate, g'', which is secured to the upper plate by bolts or rods g'', upon which it has a slight vertical movement. This lower plate closes upon the shoulders or ledges g'', and the play of the plate g'' upon the bolts or rods g'' is such that in closing the door the said plate comes in contact therewith before the plate g'' shuts upon the shoulders or ledges g''.

The fire-pot C conforms to the general shape of the stove, preferably has rounded corners, 85 and a lining of iron-stone or fire-brick, which, upon the sides and front, does not extend to the grate B, and the section of the fire-pot between the side and front lining and the grate B comprises inclined grate-bars b. The back 90 of the fire-pot is lined from the horizontal grate B to the point c.

The stove is further provided with two doors, H, one above the other, on each side, and in addition to the double door f upon the front 95 and below at the double door H''. These doors preferably have set in their frames transparent mica plates, one set upon a line, in whole or in part, with the portion b of the fire-pot, and the other set surrounding upon the sides and front 100

the combustion-chamber. By means of these doors access to all parts of the fire and fire-pot is easily obtained.

Unlike the ordinary base-burning stove, this stove is made so low that the magazine can very easily be supplied with coal, and when the open-grate attachment is used the self-feeding magazine is also employed, and we believe that this is the first instance where a portable open grate has been provided with a self-feeding magazine.

The swinging plate for varying the size of the outlet to the magazine may of course be upon either side, or at the back of the magazine instead of at the front, without departing from the spirit of the invention.

It will be observed that the stove is rectangular in cross-section, and that the base portion projects at the front only; also, that the fire-pot is rectangular in cross section, and that the magazine is rectangular in cross-section; further, that the mica lights may be used upon the sides or front only. This shape of fire-pot and combustion-chamber and frame of stove enables the fuel to be used to its best advantage, both for heating and illuminating purposes.

Having thus fully described our invention, we claim and desire to secure by Letters Patent of the United States—

1. A magazine or base-burning stove having 30 the plate or section supporting the doors of the combustion-chamber removable, whereby the stove is adapted to be converted from a close to an open grate, all substantially as described.

2. In a magazine or base-burning stove, a 35 removable door-supporting front plate, F, all substantially as and for the purposes described.

3. The combination of the plate e' , forming a portion of one of the walls of the magazine, hinged at e^2 to the magazine, substantially as 40 shown and specified, and means for moving the same to and from the remaining walls of the magazine to diminish or increase the size of its opening, all substantially as described.

4. A magazine or base-burning stove having 45 interchangeable front plates or sections, each of which contains the opening to the combustion-chamber, one of which is provided with doors, and the other is adapted to receive a blower, whereby the stove may be used as a 50 close or open grate, all substantially as described.

JOHN MAGEE.
